PUMPING DEVICE

Walter Shallenberg, Salem, Ohio, assignor to The Deming Company, Salem, Ohio, a corporation of Ohio

Application July 24, 1945, Serial No. 606,857

2 Claims. (Cl. 103—260)

1

This invention relates to an improvement in the jets of deep well pumps. Such jets, located in the well and supplied with liquid under pressure from the pumping mechanism above the ground and forcing such liquid upwardly in the suction pipe leading to the pump, have been found quite satisfactory when installed. A difficulty has developed, however, that when the jet nozzle or the jet tube into which it discharges becomes clogged with dirt it was necessary to pull out of the well the suction pipe, the pressure pipe (if an external pipe is employed) and the jet body in order to allow access to the jet nozzle or jet tube. The same situation arose where it was found desirable to change the size of an installed nozzle or tube.

The object of this invention is to avoid the difficulty mentioned by providing a jet nozzle and jet tube so constructed and mounted that they may be readily withdrawn through the suction pipe without disturbing either the suction pipe or the pressure pipe or the jet body which contains the suction and pressure passageways to the tube and nozzle. The means by which I accomplish this result is illustrated in the drawing hereof and is hereinafter more fully described.

In the drawing, Fig. 1 is a sectional side elevation partly broken away of a pump with a suction pipe, an external drive pipe and my improved jet; Fig. 2 is an enlarged vertical section in a plane indicated by the line 2—2 on Fig. 1 and on a larger scale; Fig. 3 is a vertical section on the same plane as Fig. 2 showing the jet pipe and jet nozzle in the act of being withdrawn through the suction pipe.

In Fig. 1, 10 indicates any suitable pump supplied by a suction pipe 11 and discharging into a delivery pipe 12. Secured to the lower end of the suction pipe 11 is the jet body 20 which has within it a passageway 21 leading from the lower end of the jet body to the suction pipe, and another passageway 22 leading to the jet nozzle 23.

In Fig. 1, I have shown a pressure pipe 15, at the side of the pipe 11 communicating at its upper end with the discharge of the pump and at the lower end with the passageway 22 in the jet body. If desired, in place of a pipe 15 at the side of the suction pipe 11, one may employ a pipe surrounding the pipe 11 and utilizing the annular space between the two pipes as the conduit for the driving pressure, the annular space in this case communicating with a similar passageway 22 leading to the nozzle. Each form of pressure pipe is well known in practice and the

jet flow from suction and drive pressure will be maintained and will be directed to the outlet of the nozzle 23 in a manner to give the desired results.

Fig. 2 shows the jet body 20 in a vertical

position and the jet tube 30 withdrawn from the

jet body 20. Fig. 3 shows the jet tube 30

in a vertical position and the jet nozzle 23

in a horizontal position.

Fig. 61 shows the jet body 20 and jet tube 30

in a vertical position and the jet nozzle 23

in a horizontal position.

Fig. 62 shows the jet body 20 and jet tube 30

in a vertical position and the jet nozzle 23

in a horizontal position.

Fig. 63 shows the jet body 20 and jet tube 30

in a vertical position and the jet nozzle 23

in a horizontal position.

Fig. 64 shows the jet body 20 and jet tube 30

in a vertical position and the jet nozzle 23

in a horizontal position.

Fig. 65 shows the jet body 20 and jet tube 30

in a vertical position and the jet nozzle 23

in a horizontal position.

Fig. 66 shows the jet body 20 and jet tube 30

in a vertical position and the jet nozzle 23

in a horizontal position.

Fig. 67 shows the jet body 20 and jet tube 30

in a vertical position and the jet nozzle 23

in a horizontal position.

Fig. 68 shows the jet body 20 and jet tube 30

in a vertical position and the jet nozzle 23

in a horizontal position.

Fig. 69 shows the jet body 20 and jet tube 30

in a vertical position and the jet nozzle 23

in a horizontal position.

Fig. 70 shows the jet body 20 and jet tube 30

in a vertical position and the jet nozzle 23

in a horizontal position.

Fig. 71 shows the jet body 20 and jet tube 30

in a vertical position and the jet nozzle 23

in a horizontal position.

Fig. 72 shows the jet body 20 and jet tube 30

in a vertical position and the jet nozzle 23

in a horizontal position.

Fig. 73 shows the jet body 20 and jet tube 30

in a vertical position and the jet nozzle 23

in a horizontal position.

Fig. 74 shows the jet body 20 and jet tube 30

in a vertical position and the jet nozzle 23

in a horizontal position.

Fig. 75 shows the jet body 20 and jet tube 30

in a vertical position and the jet nozzle 23

in a horizontal position.

Fig. 76 shows the jet body 20 and jet tube 30

in a vertical position and the jet nozzle 23

It will be seen that the jet nozzle and the jet tube while mounted in the usual position and acting in the usual manner are removable upwardly as a unit by simply applying a pulling action to the jet tube. The jet tube has means for attachment of some pulling tool; for instance, the jet tube may be threaded on the interior at the upper end, as shown at 39. Then when it is desired to remove the jet tube and nozzle it is only necessary to lower into the suction pipe a pipe or rod threaded at its lower end which may be screwed into the thread 39. Such rod is shown in Fig. 3 at 40 with the threaded lower end 41 thereof screwing into the thread 39 of the jet pipe.

Fig. 3 shows the removable parts in the act of being removed, the withdrawing rod 40 having been attached and having moved both the jet tube and the jet nozzle upwardly, freeing both of them from the jet body. It will be seen therefore that in changing the nozzle or tube it is only necessary to provide access to the upper end of the suction pipe and then to insert the removing rod and screw it into the jet body and pull upwardly on the rod until the tube and nozzle are extracted, after which they may be cleaned or repaired and replaced, or a substitute supplied as desired.

A foot valve is normally used below the jet and I find it very convenient to carry the same by the jet body. I have shown a tubular extension 50 mounted on the lower end of the jet body 20 and having a transverse partition 51 with an opening providing a valve seat, I have shown a valve 52 coacting with this seat. The valve has a downwardly extending stem 53 slidably mounted in a suitable spider-like portion 55 of the extension, and a helical spring 56 surrounding the stem, and compressed between the spider 55 and a shoulder on the stem, tends to maintain the valve on the seat in addition to the action of gravity.

The same tubular extension 50 may, if desired, carry a screen as for instance the cup 60 shown in Figs. 1 and 2. This cup may be conveniently held in place by screw bolts 61 (Fig. 2) screwing into the spider 55.

I claim:

1. In a jet construction for a deep well pump-

ing system, the combination of a jet body having a suction passageway with a cylindrical opening adjacent the upper end, a pressure passageway terminating in a conical opening axially aligned with said cylindrical opening, and a unitary jet tube and jet nozzle removably mounted in both passageways, said jet tube having a cylindrical enlargement with an annular groove, packing seating in the groove and bearing against the cylindrical opening of the body, said tube having an extension externally conical to make a tight connection with said conical opening and having an internal bore, the nozzle tightly seating in said bore and having an external flange engaging the lower end of the extension, there being a lateral opening in the extension, at the side of the nozzle communicating with the entrance to the tube.

2. The combination with a suction pipe and a pressure conduit of a jet body secured at its upper end to the suction pipe, an extension secured at the lower end of the jet body and carrying a foot valve, the jet body having two passageways, one connecting the space above the foot valve with the suction pipe and the other connecting an internal space with the pressure conduit, a jet tube removably mounted in the jet body, a jet nozzle carried by the tube, the tube being in communication with the suction passageway in the body and the nozzle in communication with the pressure passageway in the body, the jet tube and nozzle being withdrawable as a unit through the suction pipe.
